[57] CLAIM

The ornamental design for a flower pot cover, as shown
and described.

DESCRIPTION

FIG. 1 is a perspective view of a flower pot cover
showing my new design;

FIG. 2 is a top plan view thereof;

FIG. 3 is a bottom plan view thereof;

FIG. 4 is a side elevational view thereof, all-sides being
identical;

FIG. 5 is a side elevational view of a second embodiment
of the design of FIG. 1, the only difference being
the arrangement of the apertures;

FIG. 6 is a side elevational view of a third embodiment
of the design of FIG. 1, the only difference being the
arrangement of the apertures;

FIG. 7 is a side elevational view of a fourth embodiment
of the design of FIG. 1, the only difference being the
arrangement of the apertures;

FIG. 8 is a top plan view of a fifth embodiment of the
design of FIG. 1, the only difference being the configu-
ration of the apertures;

FIG. 9 is a side elevational view of FIG. 8;

FIG. 10 is a side elevational view of a sixth embodiment
of FIG. 1, the only differences being the arrangement
and configuration of the apertures;

FIG. 11 is a side elevational view of a seventh embodiment
of FIG. 1, the only differences being the arrange-
ment and configuration of the apertures;

FIG. 12 is a side elevational view of an eighth embodiment
of the design of FIG. 1, the only differences being
the arrangement and configuration of the apertures.

The horizontal and diagonal cross-hatching shown
on the inner and outer surfaces, respectively, is intended to
be symbolic of contrasting conventional surface effects
which extend entirely across each side. The flower pot
cover has no substantial thickness.
